ELECTRONIC VACUUM TUBE

Adolph A. Thomas, New York, N. Y., assignor to
 Radio Corporation of America, New York, N. Y.,
 a corporation of Delaware

Application December 31, 1929, Serial No. 417,617

31 Claims. (Cl. 250—27.5)

This invention is for an electronic vacuum tube of novel construction and capable of a variety of uses, among which I may particularly mention amplifying electric impulses, producing alternating current from a source of direct current, and rectifying alternating currents. The characteristic feature of my invention is a vacuum tube having two grids and two plates arranged to provide two electron paths. The two grids are connected to opposite sides of an input coil and are therefore always at opposite potential. When my tube is used as an amplifier or producer of alternating current from direct current, the anodes are connected to opposite sides of an output coil, and the center of this coil is connected to the positive terminal of a source of substantially constant current. The negative side of the source of plate current is connected to one end of the filament. As a result of this novel tube structure, the current through the output coil in the plate circuit is reversed with reversal of potential on the two grids, whereby increased amplification is obtained in the secondary coil of the output transformer. This permits the use of fewer tubes to obtain the required degree of audio amplification in a radio receiver and other electric translating systems. The arrangement of the five electrodes in the tube reduces the inherent capacity of the tube to a negligible quantity.

Viewed in another aspect, my invention comprises an electronic tube in which at least one set of operative electrodes is supported by novel means in such a way that the electrodes are braced at the top and bottom against axial and lateral displacement. This permits rough handling of the tube without danger of disturbing the original alignment of the electrodes.

The novel features and practical advantages of my invention will be understood from a description of the accompanying drawing, in which—

Fig. 1 is an enlarged perspective view of a vacuum tube constructed in accordance with my invention, certain parts of the tube being sectioned for clearness;

Fig. 2 shows a detached view, partly sectioned, of the electrode assembly and mounting;

Fig. 3 represents a transverse section on line 3—3 of Fig. 2; and

Figs. 4 and 5 indicate diagrammatically the circuit connections of the tube and the theory of operation.

A vacuum tube 10 has an assembly of electrodes comprising a filament 12, two anodes 13

and 13' and two grids 14 and 14'. These electrodes are supported in a frame comprising a pair of insulating plates 15 and 16 and metallic side rods 17 and 17'. The supporting plates 15 and 16 may consist of bakelite, glass, fiber, mica, porcelain, and other suitable material. The side rods 17 and 17', which are of good conducting metal, pass through holes 18 in plates 15 and 16, and the projecting ends of the rods are flattened at 19 to hold the plates in fixed relation.

The anodes 13 and 13' are shown in the form of metal cylinders inserted at their ends in circular grooves 20 in plates 15 and 16. The grids 14 and 14' are also cylindrical and their ends fit tightly in circular grooves 21 in plates 15 and 16. As seen in Figs. 2 and 3, the circular grooves 20 and 21 hold each pair of electrodes 13—14 and 13'—14' in permanent concentric relation. In the drawing the electrodes are spaced for clearness more than is necessary, but in actual practice the electrodes are mounted as closely together as mechanical conditions permit. The grids 14 and 14' may consist of wire mesh, slotted or perforated tubes, wire wound spirally over an open cylindrical frame, or of any other practical construction. It is understood that the side rods 17 and 17' are not flattened at 19 until after the cylindrical anodes and grids have been properly positioned between the supporting plates 15 and 16. The concentric grooves 20 and 21 facilitate the proper assembling of the anodes and their associated grids.

The filament 12 may consist of a single wire comprising a section 12a passing through the common axis of the concentric electrodes 13—14, a second section 12b passing centrally through the concentric electrodes 13'—14', and a top section 12c which is pushed upward by an expanding coil spring 22. The filament wire 12 passes through small holes in the insulating plates 15 and 16, and these holes are so arranged that the parallel sections 12a and 12b of the filament are substantially in the center of the two pairs of cylindrical electrodes 13—14 and 13'—14' after the parts have been assembled in the supporting frame. The spring 22 holds the filament sections 12a and 12b constantly taut. In the broader aspect of my invention, it is not necessary that the parts 12a, 12b and 12c shall be a single wire, but that is the most convenient way to make the filament. In fact, the electrode 12 may be any element capable of emitting a flow of electrons when heated. This heating may be effected in any practical way, as for example by passing a current through the filament.

The lower insulating plate 16 carries a pin 23 which is set firmly into the glass press 24 of the tube, whereby the five electrodes are mounted as a unitary structure. The ends of filament 12 are 5 connected to a pair of conducting rods or stiff wires 25 and 26, which are connected by wires 27 and 28 to contact pins 29 and 30 projecting from the bottom of the tube. The two anodes 13 and 13' are electrically connected to the metal side 10 rods 17 and 17', which are connected at their lower ends to wires or rods 31 and 32, and wires 33 and 34 connect the conductors 31 and 32 to contact pins 35 and 36. The two grids 14 and 14' are connected to conducting rods 37 and 38, which 15 are connected by conductors 39 and 40 to contact pins 41 and 42. The connections between the electrodes and their respective conducting rods are most conveniently obtained by brazing or soldering, but any other practical method may 20 be employed. The six connecting rods or wires 25, 26, 31, 32, 37 and 38 are set rigidly into the top of press 24, so that they remain firmly in position.

Referring to the circuit diagrams of Figs. 4 and 25 5, the grids 14 and 14' are connected to the opposite sides of an input circuit 43 which has a coil 44 adapted to receive electric impulses. This circuit is shown in simplified form and might 30 contain such other electric elements as are necessary for proper operation in any particular system. Since the grids are thus connected to opposite sides of input coil 44, they will always be at opposite potential. That is to say, when grid 14 has a positive charge, the other grid 14' has a 35 negative charge, and vice versa. The two anodes 13 and 13' are connected by wires 45 and 46 to opposite sides of a transformer coil 47, which may be regarded as consisting of two sections 47a and 47b connected at their junction to the positive 40 side of battery B by a conductor 48. For convenience I shall refer to the coil sections 47a and 47b as coils, because they can be regarded as separate coils connected at one end. When the system is used for amplifying electric impulses or 45 for producing alternating current from direct current, the battery B represents any suitable source of substantially constant direct current of the required voltage. In that case, the anodes 13 and 13' are always at positive potential, and 50 the coil 47 constitutes a primary output coil. A secondary coil 49 is connected to a suitable translating device, such as a loudspeaker, or it may be connected to the two grids of the next tube in the system. Although I have only shown one tube 55 10 in Figs. 4 and 5, it is evident that a plurality of such tubes may be connected to obtain the required amplification, as is customary in various types of radio receivers. The filament 12 receives heating current from a battery 50, or any other 60 source of current to provide a flow of electrons to the associated grids and anodes. It is understood that the filament sections 12a and 12b are heated alike, so as to emit electron streams of substantially the same strength or density.

65 In the operation of the foregoing system as an amplifier or producer of alternating from direct current, let us assume that at a given moment the grid 14 is positive and grid 14' negative, as indicated in Fig. 4. Grid 14 therefore attracts 70 the electrons, while the other grid repels them. Consequently, an electronic conducting path is established between filament 12 and anode 13, this path being diagrammatically indicated by the dotted area 51. The circuit of battery B is 75 now closed through conductor 48, coil 47b, con-

ductor 45, anode 13, electronic path 51, filament 12 and back to the battery through return wire 52. The current passes through coil 47b in the direction of arrow b. When the grid 14' is positive and the other grid 14 is negative, as indicated in Fig. 5, an electronic conducting path 51' is established between filament 12 and anode 13', so that the plate current now passes through coil 47a in the direction of arrow a. In other words, when grid 14 is positive, the plate current passes 10 through coil 47 in one direction and when grid 14' is positive, the plate current passes through coil 47 in the reverse direction. Putting this differently, I may say that reversals of potential charges on grids 14 and 14' produce amplified reversals of current flow (i. e. alternating current) in the primary output coil 47, and these alternations of current induce corresponding current variations in the secondary output coil 49, which may be in step-up relation to coil 47. 20

The reversals of current in output coil 47 produce greater amplification of induced currents in coil 49 than is possible by mere fluctuations of current without actual reversal of flow. This is in accordance with well known electromagnetic 25 laws. In electronic vacuum tubes heretofore used, the plate current merely fluctuates in response to variations of grid potentials; that is, the current varies in intensity but always flows in the same direction. By reversing the flow of current in the primary output coil 47, I obtain induced currents of maximum intensity in the secondary coil 49, so that less tubes are needed to obtain the desired amplification in the final output stage of the system. 30

It is possible that when the electron path 51 is established between electrodes 12 and 13, as indicated in Fig. 4, the negative grid 14' does not prevent all electrons from reaching the anode 13', so that a very feeble current might flow through 40 coil 47a in opposition to the heavy current through coil 47b. However, the opposing electromagnetic effect of any such slight current in coil 47a would be practically negligible. This also applies to the momentary condition of the 45 system in Fig. 5. Since the potential charges on grids 13 and 13' are periodically reversed, it is impossible for electrons to accumulate on either grid, so that no grid leak is necessary. 35

When my new tube is used for rectifying alternating currents, coil 49 is connected to the alternating source and becomes the primary input coil, while coil 47 becomes the secondary input coil. The two grids 14 and 14' are connected by wires 53 and 54 to opposite sides of coil 49. The coil 55 44 is of course not required now, and battery B is replaced by a direct-current consuming device. As the current alternates through coil 49, the potential charges on grids 14 and 14' change accordingly, and the induced alternating currents in coil 47 change in the same way. For instance, when the current in coil 49 flows in the direction of arrow c, the potential on grid 14' is positive and that on grid 14 is negative. The induced current in coil 47 flows in a direction opposite to the flow of primary current, so that anode 13' is positive and anode 13 is negative. An electronic conducting path is therefore established between filament 12 and anode 13', so that current flows through translating device B in the 70 direction of arrow d.

Let us now suppose that the current flows through primary coil 49 in the direction of arrow e, so that grid 14 is now positive and grid 14' negative. The induced current in coil 47 flows 75

in the direction of arrow *b*, so that anode 13 is positive and anode 13' negative. An electronic conducting path is established between filament 12 and anode 13 to complete the circuit through translating device B in the direction of arrow *d*, the same as before. The entire coil 47 does not operate at each alternation, for the current flow through translating device B in the same direction is completed alternately through coil sections 47a and 47b. It is customary to insert choke coils and condensers for smoothing out current ripples in the rectified circuit, as will be understood without further explanation. Since the grids 14 and 14' are in an open shunt across coil 49, they consume no power in the operation of the rectifying system.

Although I have shown and described a specific construction of vacuum tube and circuit connections therefor, my invention is not limited to the details set forth. In the broader aspect of my invention the particular form, mounting and arrangement of the electrodes are immaterial, so long as the desired result is obtained. Changes and modifications may be resorted to without departing from the scope of the invention as defined in the appended claims.

I claim as my invention:

1. An electronic vacuum tube having a cylindrical anode, a cylindrical grid within said anode, a support comprising a pair of spaced insulating plates having circular recesses for receiving the opposite ends of said anode and grid to hold the same in concentric relation, whereby the ends of said anode and grid abut against said plates and hold the latter spaced, so that any tendency of the plates to move toward each other increases the pressure of the engagement between said plates and said electrodes, a filament mounted substantially in the axis of said concentric electrodes, and a plurality of stiff rods connecting said plates independently of said cylindrical electrodes and rigidly holding said plates against separation.

2. An electronic vacuum tube provided with a pair of insulating supports held in spaced parallel relation, a pair of cylindrical anodes mounted rigidly side by side between said supports, a cylindrical grid mounted in each anode, cooperating means on said supports and said grids for holding the latter in substantially concentric relation to the associated anode, said spaced insulating supports holding the two anodes insulated from each other and also holding the two grids insulated from each other, an electronic filament having portions substantially in the axes of said pairs of cylindrical electrodes, and a plurality of stiff rods connecting said supports independently of said cylindrical electrodes and rigidly holding said supports against separation.

3. An electronic tube comprising a pair of insulating plates, a plurality of rigid electrodes supported by and between said plates, means independent of all electrodes for rigidly connecting said plates and locking them against separation, other means for rigidly supporting the connected plates and electrodes as a unit, and means for locking the ends of said electrodes to said plates, and electronic means in operative relation to said electrodes.

4. An electronic tube comprising a pair of insulating plates supported transversely of the tube, a pair of cylindrical electrodes supported by and between said plates in concentric relation, means independent of said cylindrical electrodes for rigidly connecting said plates and locking them against separation, other means attached to at

least one of said plates for rigidly supporting the connected plates and said electrodes as a unit, means for locking the ends of said electrodes to said plates, and electronic means in operative relation to said electrodes.

5. An electronic tube comprising a pair of insulating plates, a plurality of electrodes supported by and between said plates in operative relation, said electrodes including electronic means, a tie rod connecting said plates and locking them against separation, said tie-rod being conductive and in electrical contact with one of said electrodes, and means independent of said tie rod for supporting the connected plates and electrodes as a unit.

6. An electronic tube having a plurality of sets of electrodes, each set comprising a filament, an anode and an interposed grid, said anodes being insulated from each other and each anode at least partially surrounding the associated filament, the anode of each set of electrodes being shielded from the electron stream emitted by the filament of the other set, a pair of transverse plates by and between which said sets of electrodes are supported side by side in spaced relation, said plates and the opposite ends of said anodes and grids being in firm engagement, so that said anodes and grids constitute spacing means for said plates, and a plurality of stiff rods connecting said plates independently of all electrodes and locking said plates against separation.

7. An electronic tube comprising a pair of insulating plates supported transversely of the tube and provided with circular grooves, a pair of cylindrical electrodes supported by and between said plates, the ends of said electrodes extending into said grooves, whereby said electrodes are locked against displacement, means independent of said cylindrical electrodes for rigidly connecting said plates and locking them against separation, and other means attached to at least one of said plates for rigidly supporting the connected plates and said electrodes as a unit.

8. An electronic tube having a cylindrical anode, a cylindrical grid within said anode, a support comprising a pair of spaced insulating plates rigidly connected, means on said plates for holding said anode and grid in concentric relation, said plates and the opposite ends of said anode and grid being in firm engagement, so that said electrodes constitute spacing means for said plates, a filament engaging said plates and mounted substantially in the axis of said concentric electrodes, means independent of said electrodes for locking said plates against separation, and a separate member connected to at least one of said plates for rigidly supporting said plates and electrodes as a unit.

9. An electronic tube comprising a one-piece filament having two taut sections substantially parallel, a rigid insulating support for holding said sections spaced apart, said parallel sections being joined by a transverse section of filament above said support, means carried by said support for tensioning said transverse section to hold said parallel sections taut, said parallel sections being held in spaced relation by said support independently of said tensioning means, and at least one electrode in operative relation to each of said parallel sections, each electrode being shielded from the electronic emission of the filament associated with the other electrode.

10. An electronic tube comprising a pair of transverse insulating plates, a tie rod for holding said plates against separation, electrodes oper-

atively mounted between said plates, at least one of said electrodes being rigid and engaging said plates and holding them spaced apart, whereby said rod and rigid electrode cooperate to maintain said plates firmly in predetermined spaced relation, and a rigid post connected to at least one of said plates for supporting the connected plates and said electrodes as a unit.

11. An electronic tube comprising a central rigid post projecting from its base, an insulating plate secured to said post, a pair of rods projecting upwardly from the ends of said plate, a second insulating plate engaging the upper ends of said rods and held substantially parallel with the lower plate, means whereby said rods lock said plates against separation and a plurality of electrodes engaging said plates and rigidly held thereby in spaced relation, said electrodes being stiff and holding said plates against movement toward each other.

12. An electronic vacuum tube provided with a pair of insulating plates held in spaced parallel relation, a pair of cylindrical anodes mounted rigidly side by side between said plates, a cylindrical grid mounted in each anode and held by said plates in substantially concentric relation to its anode, the opposite ends of said cylindrical anodes and grids engaging said plates and rigidly holding the latter against movement toward each other, an electronic filament having portions mounted substantially in the axes of said pairs of cylindrical electrodes, and a pair of metallic tie rods engaging said plates and preventing separation thereof, said rods being in contact with said anodes and constituting conductors therefor.

13. An electronic vacuum tube comprising a substantially rectangular frame rigidly supported axially of the tube, said frame having upper and lower cross members provided with a plurality of recesses, a pair of electrodes of cylindrical shape supported by and between said cross members in substantially concentric relation, said electrodes having portions extending into said recesses, whereby the electrodes are locked against relative displacement, and a plurality of stiff rods for connecting said members independently of said electrodes and rigidly holding said members against separation.

14. An electronic vacuum tube containing a one-piece filament which has two taut sections substantially parallel and held spaced apart, said parallel sections being joined by an integral transverse section, spring means acting upon the central portion of said transverse section in a direction substantially parallel with said two parallel sections, whereby said transverse section is held constantly under tension to maintain said two parallel sections taut, and a pair of spaced anodes in operative relation to said filament sections, each anode at least partially surrounding one of said sections and being shielded from the electronic emission of the other section.

15. An electronic vacuum tube comprising a set of electrodes operatively positioned in the direction of the axis of said tube, said electrodes including an electron-emitting element, a rigid support for said electrodes, said support including a pair of spaced insulating plates for the top and bottom of said electrodes to hold the latter securely against axial and lateral displacement, said element engaging said support at the top and bottom only, so that the electron-emitting portion of said element is wholly out of contact with said support, said element passing through the

upper plate of said support, and means on said upper plate for engaging said element.

16. An electronic vacuum tube having two cylindrical anodes mounted in spaced relation and insulated from each other, a cylindrical grid mounted centrally within each anode, said grids being insulated from each other and from said anodes, an electronic filament comprising two parallel sections each of which is located substantially in the axis of one pair of said nested cylindrical electrodes, an insulating cross-plate rigidly supported and engaging the upper ends of said cylindrical anodes and grids to hold them firmly in position as a unit, and six contact members projecting from said tube and electrically connected to said five electrodes as follows: two of said contact members being connected to said pair of insulated anodes, other two contact members being connected to said pair of insulated grids, and the remaining contact members being connected to the ends of said filament.

17. An electronic vacuum tube having the usual press at the bottom, a rigid post carried by said press, an insulated plate mounted on said post, a second insulated plate vertically spaced from said first plate, an electrode assembly mounted on and between said spaced plates, said assembly comprising at least one cylindrical anode and one cylindrical grid within said anode, said nested cylindrical electrodes engaging said plates at both ends and holding them spaced apart, a plurality of stiff rods connecting said plates independently of said electrodes and preventing separation of said electrodes, and leading-in wires embedded in said press and connected to said electrodes, said post forming a rigid support for the connected plates and electrode assembly independently of said wires.

18. An electron discharge device having in combination with a cathode and grid, a pair of supporting rods on opposite sides of said cathode and grid, an anode carried by one of said rods, an insulating plate at one end of the anode secured thereto, and means for securing said plate with respect to the other support rod.

19. An electron discharge device having in combination with a cathode and grid, a pair of supporting rods on opposite sides of said cathode and grid, an anode carried by one of said rods, an insulating plate at one end of the anode secured thereto, a grid connection engaging said plate for holding it against movement in one direction, and means on the opposite side of said plate for holding it against movement in another direction.

20. In an electron discharge tube, a unitary structure supported therein comprising a hollow plate electrode, insulating caps at the ends of the hollow plate, said caps having annular grooves, a heater-cathode element supported by said caps in axial position within the hollow plate, and a hollow grid supported by the grooves in said caps in surrounding position relatively to the heater-cathode, the caps having orifices for the passage of the terminals of the heater-cathode and grid.

21. In an electron discharge tube, a unitary structure supported therein comprising a hollow plate electrode, insulating caps at the ends of the hollow plate, said caps having annular grooves, a heater-cathode element supported by said caps in axial position within the hollow plate, and a hollow grid supported by the grooves in said caps in surrounding position relatively to the heater-cathode, said grid comprising a wire coil

- to one side of which is welded a terminal wire parallel with the axis of the coil, the caps having holes receiving through them the ends of said grid terminal wire.
- 5 22. In an electron discharge tube, a unitary structure supported therein comprising a cylindrical plate electrode, insulating caps at the ends of said cylindrical plate, said caps having annular grooves, a heater-cathode element supported by said caps in axial position within the cylindrical plate, a hollow grid supported by the grooves in said caps in surrounding position relatively to the heater-cathode, and means for supporting said unitary structure comprising a sufficiently heavy wire projecting from the press of the tube and welded to the side of the cylindrical plate.
- 10 23. In an electron discharge device, a cathode, a tubular grid, a tubular anode, and insulator caps on both ends of said anode, said caps having concentric grooves for spacing the cathode, grid and anode.
- 15 24. An electrode assembly comprising a pair of insulating members and a plurality of electrodes, including cathode, anode and control grid, said insulating members having a number of parallel projections thereon to separate the ends of said electrodes, and means including said projections for maintaining all of said electrodes in concentric spaced relation.
- 20 25. An electric discharge device comprising an enclosing receptacle, insulating blocks within said receptacle, said blocks having a plurality of similar projections, and cathode, grid and anode electrodes seated in said blocks and maintained in spaced relation by said projections.
- 25 26. A tube comprising an enclosing envelope, a plurality of filaments, a plate adjacent each filament separately surrounding the same, upright supports for the plates, a member fastened to said supports and fitting snugly between and against the opposed outer surfaces of the plates and holding the latter from movement relative to each other, said member being in the form of a sheet of insulation mounted in a plane extending substantially at right angles to the axes of said plates.
- 30 27. A tube comprising an enclosing envelope, a pair of spaced cathodes, a pair of anodes each separately surrounding a corresponding one of said cathodes, and a sheet of insulating material extending between the anodes and at right angles to the axes thereof, said sheet having opposed edges abutting against the opposed outer surfaces of said anodes to prevent relative rotation between said anodes and cathodes.
- 35 28. A tube comprising an enclosing envelope, a plurality of electron-emitting cathodes, a pair of anodes each separately surrounding a corresponding one of said cathodes, a sheet of insulating material extending between the anodes at right angles to the axes thereof, said sheet abutting against the opposed outer surfaces of said anodes, and means connecting said cathodes and said anodes to said insulating member in interlocking relation.
- 40 29. A tube comprising an enclosing envelope having a press, a support wire sealed substantially centrally in said press, a pair of lateral support wires sealed into said press, a tubular anode fastened to one of said lateral supports, another tubular anode fastened to the other of said lateral supports, an insulator member through which said central support passes and positioned between said anodes in abutting relation with the opposed exterior faces of said anodes to prevent relative rotation therebetween.
- 45 30. An electron discharge device comprising an envelope enclosing two spaced substantially parallel rods, two spaced insulating members extending transversely of said rods and attached thereto, tubular electrodes between said insulating members parallel to and individually attached to said rods, the attachment between the tubular electrodes and the rods being eccentric of the center of said tubular electrodes, means for securing the ends of said tubular electrodes to said insulating spacer members to prevent rotation of said electrodes about said rods as a center, and cooperating cathodes disposed centrally of the tubular electrodes and held spaced from said tubular electrodes by said insulating members.
- 50 31. In an electron discharge device an electrode assembly of the unit mount construction comprising two parallel rods, tubular electrodes parallel to said rods each attached along one side to one rod, spaced insulating members to hold said rods in parallel spaced relation extending transversely between said rods beyond the ends of said electrodes and joined to said tubular electrodes to prevent rotation of said tubular electrodes about said side rods, and cooperating cathodes held inside and in spaced relation to said tubular electrodes.
